UNITED STATES PATENT OFFICE.

NILS F. AMBURSEN, OF BROOKLINE, MASSACHUSETTS, ASSIGNOR TO AMBURSEN COMPANY, OF BOSTON, MASSACHUSETTS, A CORPORATION OF NEW JERSEY.

POLE.

1,121,319.

Specification of Letters Patent. Patented Dec. 15, 1914.

Application filed August 5, 1912. Serial No. 712,489.

To all whom it may concern:

Be it known that I, NILS FREDERICK AMBURSEN, a citizen of the United States, and a resident of Brookline, in the county of Norfolk and State of Massachusetts, have invented a new and useful Improvement in Poles, of which the following is a specification.

My invention relates to telegraph or other poles and its object is to improve the construction thereof in the manner hereinafter set forth.

My invention will be described by reference to the drawings which accompany and form a part of this specification, in which—

Figure 1 is a longitudinal section of my improved pole showing one way of producing the same. Fig. 2 is a transverse section 20 of the pole shown in Fig. 1. Fig. 3 is a transverse section of a modification. Fig. 4 is an elevation of the reinforcing member shown in Fig. 3. Fig. 5 is an elevation of a fence post constructed in accordance with 25 my invention.

In the particular drawings selected for more fully disclosing my invention, 1 represents a hollow core consisting in the present case of telescoping metallic sections of suitable length convenient for shipping. According to the preferred method of constructing the pole a sectional core is placed upon a mandrel formed of the sheaves 2 supported by the central rod 3, the ends of 30 which rest on the standards 4. A layer of reinforcing material, such as the wire mesh 5, is then placed over the core and a coating of concrete or cement 6 applied to the structure. While the coating 6 may be made in 35 any suitable manner, I prefer to form it by means of a cement gun or other suitable apparatus, whereby the cement or concrete is forcibly projected against the mesh.

In Fig. 5 the fence post 7 constructed as 45 above described is provided with transverse openings 8 for the wires 9, and its upper end may be closed by the concrete cap 10 cemented thereto. It will be understood of course that a similar cap may be used if 50 sired in connection with telegraph or telephone poles.

In Figs. 3 and 4 I have shown one type

of high-rib mesh, consisting in the present instance of angularly spaced longitudinally-extending rods 5' connected by zigzag transversely-extending wires 5''. This form of reinforcing member is preferred for poles 55 of the larger sizes.

The hollow core may be withdrawn if desired, as shown in Fig. 5, or may be retained to assist in strengthening the structure. It will be noted that the position of the reinforcing member is such as to strengthen the pole at the points where it 60 is subject to tensile stresses.

One of the advantages of the present invention is that the sections comprising the core can be nested together and readily shipped to the place where the pole is to be set up, and the device manufactured on the 70 spot.

In the claims I use the word "concrete" as covering cement or the like.

Various modifications may be made in the details shown and described without departing 75 from the spirit of my invention.

I claim:

1. The herein described method of forming hollow concrete posts or the like, which consists in mounting a suitable core upon a 80 support, surrounding said core with a sheet of reticulated material, forcibly projecting wet concrete against said sheet and core until covered to the desired thickness, and then withdrawing the core after the concrete is 85 set.

2. The herein described method of forming hollow concrete posts or the like, which consists in mounting a suitable imperforate core for rotation upon a shaft, surrounding 90 said core with a sheet of reticulated material, and forcibly projecting wet concrete against said core and sheet, said parts being turned on the shaft during such operation so as to insure a uniform coating of concrete on 95 all sides thereof.

In testimony whereof, I have hereunto subscribed my name this 30th day of July 1912.

NILS F. AMBURSEN.
